UNITED STATES PATENT OFFICE

170,775

PLASTIC COATED FABRIC OR SIMILAR ARTICLE

Dominic A. Saporito, Royal Oak, Mich., assignor to United States Rubber Company, New York,
N. Y., a corporation of New Jersey

Application April 24, 1953, Serial No. 24,653

Term of patent 14 years

(Cl. D87—3)

To all whom it may concern:

Be it known that I, Dominic A. Saporito, a citizen of the United States, residing at Royal Oak, in the county of Oakland and State of Michigan, have invented a new, original, and ornamental Design for a Plastic Coated Fabric or Similar Article, of which the following is a specification, reference being had to the accompanying drawing forming part thereof.

The figure of the drawing is a plan view of a plastic coated fabric or similar article showing my new design.

I claim:

The ornamental design for a plastic coated fabric or similar article, as shown.

DOMINIC A. Saporito.
